US0D1035149S

(12) United States Design Patent (10) Patent No.: US D1,035,149 S
(45) Date of Patent: * Jul. 9, 2024

(54) PERSONAL CARE PRODUCT

(71) Applicant: The Gillette Company LLC, Boston, MA (US)

(72) Inventor: Robert Andrew Kearney, Reading (GB)

(73) Assignee: The Gillette Company LLC, Boston, MA (US)

() Term: 15 Years

(21) Appl. No.: 29/779,693

(22) Filed: Apr. 20, 2021

(51) LOC (14) Cl. 28-03

(52) U.S. Cl. USPC D28/47
